UNITED STATES PATENT OFFICE

171,991

GAME BOARD

John Voetberg, Everett, Wash.

Application June 1, 1953, Serial No. 25,286

Term of patent 14 years

(Cl. D34—5)

To all whom it may concern:

Be it known that I, John Voetberg, a citizen of the United States, residing at Everett, in the county of Snohomish and State of Washington, have invented a new, original, and ornamental Design for a Game Board, of which the following is a specification, reference being had to the accompanying drawing, forming part thereof.

Fig. 1 is a top plan view of a game board showing my new design.

Fig. 2 is an edge elevational view thereof.

I claim:

The ornamental design for a game board, as shown.
